UNITED STATES PATENT OFFICE.

GEORGE H. FORSYTH, OF CHICAGO, ILLINOIS.

METAL SASH.

Application filed August 1, 1917. Serial No. 183,839.

To all whom it may concern:

Be it known that I, GEORGE H. FORSYTH, a citizen of the United States, residing at Chicago, in the county of Cook and State of Illinois, have invented certain new and useful Improvements in Metal Sashes, of which the following is a specification.

The purpose of the invention is the provision in a metal sash of constructional features making for efficiency and economy, including the providing of certain associated features which cooperate with the sash and the sash opening to effectually seal the opening when in closed position, and which overcome the difficulties heretofore encountered in the manufacture and use of sash made of light weight metal such as brass and sheet steel.

The invention includes the utilization within the metal sash frame members of removable stiffening filler strips of wood or the like which serve as an interior anchorage for the fastenings of the glazing beads, weather strips and sash hardware, thus also permitting of the use of lighter weight metal than would otherwise be required; also the assemblage of such filler strips with the frame in a particularly simple and effective manner; also the employment of fillets overlying and protecting the glass at the corners of the sash; also the protection of the glass and frame from the entrance of dirt and water back of the sash lock and lift; also the sealing of the sash within the sash opening by means of weather stripping efficiently assembled with the frame; and other interrelated features of construction which will hereinafter be apparent from the following detailed description of certain embodiments of the invention based upon the accompanying illustrative drawings. It will be understood, however, that the drawing and description are exemplary only, and that they are to be taken in an illustrative rather than in an unnecessarily limiting sense.

In the drawings:

Fig. 1 is an elevation, partly in section and broken away in their medial portions, showing one form of construction embodying the invention;

Fig. 2 is a vertical section on the line 2—2 of Fig. 1;

Fig. 3 is a horizontal section on the line 3—3 of Fig. 1;

Fig. 4 is a vertical section on the line 4—4 of Fig. 1;

Fig. 5 is a vertical section showing a modification of Fig. 2;

Fig. 6, 6^a and 7 are vertical sections showing modifications of Fig. 4;

Fig. 8 is a detailed sectional view showing slight modifications of corresponding structures included in Fig. 2 and 3;

Fig. 9 is a detailed cross-section of the glass backing strips shown in Figs. 2 and 8;

Fig. 10 is a front elevation, similar to Fig. 1, but illustrating a modification;

Fig. 11 is a vertical section on the line 11—11 of Fig. 10;

Fig. 12 is a horizontal section on the line 12—12 of the Fig. 10;

Fig. 13 is a vertical section on the line 13—13 of Fig. 10;

Fig. 14 is a vertical section showing a modified form of construction;

Fig. 15 is a vertical section taken through a portion of the lock and illustrating its form of attachment to the frame;

Fig. 16 is a view similar to Figs. 1 and 10 but illustrating a further modification;

Figs. 17, 18 and 19 are cross-sectional views taken respectively on the lines 17—17, 18—18 and 19—19 of Fig. 16; and

Fig. 20 is a vertical cross-section through the bottom rail showing a modified form of cushion construction and of assemblage.

Fig. 21 is a vertical section showing a further modification of Fig. 2.

Having reference particularly to Figs. 1 to 4 inclusive, a hollow sash frame is shown as composed of a top rail 21, a bottom rail 22, and side rails or stiles 23. The rails are tubular in form, being closed along their outer edges, whereas the stiles are of general U-cross section being open along the outer edges, and the adjacent ends of the stiles and rails are mitered and fixedly connected by means of L-shaped inserts 24. The intermediate portions of the rail and stile interiors are reinforced by means of tubular or channel members 25 of sheet metal, the ends of which abut against the corner L-inserts 24.

When the sash frames are made of thin metal such as sheet brass, difficulty is encountered in providing a suitable anchorage for the screws by means of which the removable adjunctive sash elements such as glaz-

ing beads, indicated at 26, are held in position, it being usual to employ machine screws for this purpose although the thinness of the metal affords an insecure anchorage for the thread of the screw. An important feature of the present invention is the provision of interior filler members or strips of wood or the like which constitute a firm anchorage for wood screws 27 extending through the outer metal shell, or this filler may be of metal and serve as an anchorage for machine screws, or the anchorage may consist of both wood and metal for both wood and machine screws. It must be evident that such interior anchorage members also serve to reinforce the thin walls of the rails and stiles against injury either of deflection or indentation. It is possible that in combination with such anchorage members such as metal that other than screws may be employed. Also it must be evident that such anchorage means may consist of small unitary portions of the sash elements themselves; also that these anchorage members whether of strips or small members may be carried in lateral channels, slits or pockets in the rails and stiles, as well as in the interior thereof as shown in Fig. 21.

As herein shown, the filler strips 28 for the stiles 23 have a vertical edge-groove 29 for cooperation with weather stripping 30 (Fig. 3), although the groove 29 may be omitted. In either case, the projecting edges of the wooden filler strips are subject to being planed down as may be necessary in order to secure a proper lateral fit for the sash. The filler members 31 and 32 of the rails 21 and 22 respectively have a plain surface lying closely adjacent the outer shell portion of the rail in order to support the same and afford anchorage for the screws 33 of the top weather stripping 34 and the screws 35 of the lower sash cushion 36.

The filler members are inserted in the manner following: The upper strip 31 and the lower strip 32 are readily inserted from either side transversely to the upper and lower ends of the stiles 23, the latter being open as previously stated. After the insertion of the filler strips 31 and 32, the filler strips 28 are placed in position and serve to lock the strips 31 and 32 against withdrawal, being themselves held in position against vertical displacement at the upper and bottom edges of the rails and against lateral displacement by engagement with the weather stripping or the bottom of the guide channels. They are additionally held in position by means of the screws 27 of the removable glazing beads which are seated therein.

A modification of the above described construction is illustrated in Figs. 5, 6 and 7, wherein the upper and lower rails, while

hollow, are not of tubular form, but open along their outer edges, the upper weather stripping 37 (Fig. 5) being carried directly by the filler strip 31 to which it is secured by the screws 38, while sash cushions 39 and 40 (Figs. 6 and 7) are directly secured to the filler strips 32 by means of the screws 41 and 42 respectively.

In Fig. 6 the bottom of the filler strip 32 is channelled as indicated at 43, and preferably rectangular for the reception of a rib 44, preferably inclined, on the cushion 39, the relative arrangement of the groove and rib being such that the remaining marginal base portions of the cushion will seat against the rail base before the rib seats within the groove and for the further reason that before assemblage, as shown at 39^a, Fig. 6^a, the margins of the strip 39 are upwardly inclined.

In Fig. 7 the cushion is shown as having a dove-tail portion 45 which interlocks with the in-turned edges 46 of the outer margin of the rail.

In each of the forms of construction shown in Figs. 4, 6 and 7 a channel retaining strip or plate 47 is used whose edges are preferably formed to force the margins of cushion strips upwardly in close engagement with the sash wall as well as forming an extensive bearing support for the screws 35, 41 and 42.

It will be observed that in each of these figures, the toe 48 of the cushion will seat upon the window sill before the heel 49, the toe having given to it during the downward movement of the sash an outward sliding or rolling movement, during which the said toe adapts itself to any variations in the window sill, while the ends of the toe enter into and bear against the front walls of the sash guide grooves, at the two sides of the sash thus preventing the entrance of dirt into the car along the sill and at the corners of the sash.

The top weather stripping, as shown in Figs. 2 and 5, consists of a flexible material overlaid by a metal strip, one of whose resilient edges tends to press the flexible strip into effective engagement for weather exclusion. The metal strip is offset for stiffening purposes. This weather stripping is attached to the anchorage or filler members as by means of screws, passing through the sash shell in Fig. 2, and in the case of Fig. 5 being connected directly to the wooden anchorage strip.

In Figs. 10 to 15 inclusive is shown a further modification in which both the rails and stiles are tubular in shape, being closed along their outer margin. Herein openings are provided which align with the interior rails and stiles as indicated at 51 and 52. The frame here illustrated is likewise fixedly connected at the corners by means

of L-shaped inserts 53 and interiorly reinforced by metal members 54, but in this instance the members 54 extend to the corners of the frame, being offset near their 5 ends to enter within the L-inserts 53.

The manner of assembling the stile filler members 55 and rail filler members 56 is as follows: The right hand filler member of strip 55 is first inserted from above 10 through the opening 52; the upper and lower filler strips 56 are then inserted in the top and bottom stiles from the left hand end through the openings 51; and finally the left hand stile filler strips 55 is 15 inserted from above through the opening 52. The filler strip 55 last inserted serves as a key by means of which the outer filler strips are firmly held in position and their dislocation prevented. They can serve as 20 interior anchorages for the screws of the adjunctive sash elements, such as the removable glazing beads, sash hardware, weather stripping, and cushions as in the previous case.

25 Having reference to Fig. 12, the metal shell forming the stile is bent inwardly upon itself in order to provide a marginal channel within which to seat a wooden bearing strip 57 which may be planed in order to 30 insure proper fit of the sash within the window frame, and to which any side weather stripping may be readily attached, as in Fig. 18 or like the top weather stripping in Fig. 5. The lower rails, also, may be similarly channeled on its lower edge, (Fig. 14) 35 to form a seat for a wood strip 58 which may be planed off and have direct contact with the window sill, or which may be provided with a groove for tongue and groove connection, with a cushion strip 58^a, the members 58 being held in position by screws 59 seated within the recesses 60, and the cushion being attached to the strip 58 by the retaining strip 58^b and the screws 58^c.

40 In Figs. 16 to 21 inclusive is shown a form 45 of construction in which the rails and stiles are joined together by means of screws 61 entering into the L-shaped corner inserts. Herein are also employed the interior metal 50 reinforcements 62 extending preferably from end to end of the sash members with their 55 end portions entering within the L-shaped corner inserts 63, without being offset as in the former case. Wood filler strips 64 and 65 are also used in the rails and stiles to 60 form an inner anchorage for the wooden screws of the removable glazing beads, and for the weather stripping and sash cushions. The interior metal reinforcing members 62 65 serve as an anchorage for the machine screws 67, likewise employed for holding the glazing bead and sash hardware in place.

In order to provide for a spring resistance or set-back to prevent the working loose of the machine screws, the reinforcing members

62 are provided with spring tongues 68 and with cupped portions 69 into which the machine screws are tapped. An appropriate form of lateral weather stripping is shown at 70 in Fig. 18, the same being attached to the wooden anchorage; and an advantageous hollow form of sash cushion is indicated at 71 in Fig. 20.

Having reference to Figs. 1 and 3 of the drawings, provision is here shown for protecting the corner portions of the glass and for facilitating the cleaning of the same. For this purpose corner fillets or aprons 75 of thin spring metal are associated with the permanent and removable glazing beads and the glass packing strips 76, the same extending in a curved outline and caused to closely hug the two faces of the glass so as to prevent the entrance of dirt and moisture. Back of the sash lock 77 and the lift 78 these corner aprons extend further into the field of the glass so as to protect the same underneath the hardware as indicated at 79. As a further protection against the elements, to prevent the entrance of dirt back of the lock and lift at the corner of the frame, a rubber strip 80 is let into the rear face of the lock plate and a similar rubber strip is let into the rear face of the lift plate as indicated at 81, the edges of these rubber strips 85 extending out to the curved contour of the lock and lift.

The aprons on the two sides of the glass 90 may be integral as indicated in Figs. 2 and 3 or it may be formed as two separate plates as indicated in Fig. 8. In either case, the lateral pressure against the two sides of the same, by means of the integral glazing bead 82 on the one hand and the removable glazing bead 26 on the other, serves to hold the 95 same securely by spring pressure against the two sides of the glass. Where the corner fillet is of integral construction it is preferably provided with a longitudinal groove 100 75^a permitting transverse yielding of the fillet relatively to the glass and the rubber glazing packing. The inwardly turned curved edges 75^b of the fillets also afford 105 yielding engagement with the glass.

In the lower portion of the separable sash 110 illustrated in Fig. 16 the fillets 75^c are formed integral with the sash shell or frame members in the process of manufacture; whereas in the upper portion, the corresponding fillets 75^d are separate from the sash members and secured thereto. In order to facilitate the assembling and disassembling of the frame, the ends of the rail or stile, are slotted at 75^e to effect slidable engagement between the parts.

115 It will be observed, having reference to Figs. 2, 3, 4, 8, 9, 15 and 18 that the glass packing strip 76 has a peculiar cross-sectional configuration, the base being longitudinally grooved along its rear at 76^a and

provided with a corresponding interior rib 76^b, the material therebetween being extra thick. It is also thickened and beveled along its margin as indicated at 76^c whereby an unusual amount of adjustability as related to variations in dimensions and thickness of glass is obtained, as well as particularly efficient cushioning and sealing of the glass within the sash frame. The thicker the glass 10 the higher will rise the edges of the rubber channel upon the glass and with a steeper pitch of the said edges to shed the water from the glass. The beveled edges not only adjust themselves to varying thicknesses of 15 glass but also overlie the adjacent edges of the permanent and removable beads shedding the water therefrom.

It will be observed that in the various forms of construction shown, the glass is 20 seated upon the glazing strip, which in turn rests upon a ledge 85 extending from the permanent bead 82 towards the open part of the frame. It will also be observed that from the ledge 85 the inner edge of the 25 frame is beveled outwardly and then inwardly as indicated at 86 and 87 (Figs. 5 and 6 for instance); also that the beveled projection 87 terminates short of the plane of the ledge 85 so as not to interfere with 30 the lateral removal of the glass and its glazing strip along said ledge 85. It will also be noted that when the removable glazing bead 26 is placed in position against the outer marginal portion of the glass and is 35 drawn into securing position by means of screws 27 the outer edge of the bead lies upon the beveled face 87 and its inner edge against the glazing strip 76 (Figs. 4 and 7). The tightening of the screws 27 causes 40 a diagonal movement of the glazing bead 26. The lower edge of the bead in Fig. 7 overlies the projection 87 and serves as an effective water-shed to prevent the access of moisture to the interior of the glazing 45 bead, while in Fig. 4 the lower edge of the glazing bead comes flush with the outer face of the sash and therefore will not strike any projection.

The sash hardware such as the lock and 50 lift are firmly secured in relation to the sash by means of screws 90 which may be machine screws tapped into the corner inserts, or in the sash constructions shown in Figs. 10 and 16 tapped into the ends of the 55 interior reinforcing channels as well as into the corner inserts, or they may be simply wood screws extending into the interior wooden strips.

Male and female screws may be employed 60 as indicated in the lower portions of the lock and lift plate of Figs. 1 and 4, with a barrel 91 having a length slightly less than the total thickness of the plate of the lock or lift, the head of the screw member 92 65 overlying the said plate and serving to

clamp the same firmly to the barrel member. Integral studs 93 or 94 carried by the lock or lift enter through the shell of the stiles and the rails and extend into the interior inserts or reinforcements and in 70 sash constructions of Figs. 10 and 16 clear into the interior channel reinforcing members entering into the corner inserts forming an interlocking attachment for the lock or lift and relieving the sash shell from undue strain, as well as distributing the strains applied to the lock or lift generally throughout the corner and sash construction.

Having reference to Figs. 1 and 3 particularly, a sheet metal channel strip 95 serves as a housing for a rack member 96 which cooperates with the plunger 97 of the lock. This rack member is secured to the base of the channel strip at intervals by means of 80 spot welding. The channel strip with the contained rack is then disposed within the guide channel 98 and secured therein by means of the screws 99 which may pass through both the channel strip 95 and rack 96. This constitutes a very cheap and at the same time efficient mounting for the rack. It will be noted in this connection that the lock plunger has a face curved from 85 its pivot as a center, whereby as the lock is operated no downward pressure is exerted on the rack.

In Fig. 15 there is shown a modified construction of sash stile or rail consisting of a tubular section 100 formed up of thin sheet metal, whose edges are made to overlap each other at 100^a, where a suitable joint can be made in a variety of ways as by solder or other means, the strength of 105 said joint being further increased by the right hand supporting wall of the corner insert 101 and top cross wall of the reinforcing channel 102. The sash lock 77^a is attached to the sash by means of screws 90^a and 103. The former is tapped into a lip 101^a of the corner insert 101, said lip being purposely flattened or so formed that the part receiving the screw thread is spaced away from the adjacent wall of the rail, so that upon the screw 90^a being tightened 115 up the effort of the lip to spring back into its released position will frictionally prevent the screw from becoming loose. The screws 103 are tapped into depressions or pockets formed in the interior reinforcing member, the walls at the threaded hole being split to increase the spring action of the same in preventing the screws 103 from becoming loose.

Fig. 21 shows another construction of 125 sash rail or stile in which the anchorage for the removable glazing bead 26 consists of a strip 105 carried normally in a groove or pocket 106 formed in the rail from 130 which the said strip can be readily re-

moved for re-drilling and re-tapping of the glazing bead screws in case any of the same are twisted off, after which the strip may be quickly reinserted into its retaining groove for the re-application of the glazing bead screws. It will be noted particularly that the strip can be removed and replaced without removing the sash from the window opening. The outer edge of 10 the rail is formed with a channel 107 adapted to receive therein a wooden filler strip 108. The latter is held in position by means of a screw 109, which is screwed into the wooden filler strip 110 lying within the 15 sash rail. The wooden strip 108 serves as an anchorage for a weather stripping 111 attached to the same by means of screws 112.

Referring again to Figs. 2, 3, 4, 8, 9, 15 20 and 18 it will be noted that the glass groove in the glass packing or rubber glazing strip is provided with a centrally raised rib 76^a on each side of which are downwardly and laterally extending fillets 76^c this raised 25 rib, especially when combined with opposite groove in the outer face of said wall affords the maximum cushioning effect for the glass, while the said fillets prevent the sharp edges of the glass from cutting into 30 the rubber channel.

I claim:

1. In metal sash construction, a tubular frame member, a wooden filler member disposed within said frame member and adapted for insertion and removal longitudinally thereof without disturbing the structure of the frame, and removable glass retaining beads anchored through the frame member in the filler member.
2. A hollow sheet metal sash having edge openings in communication with the rails and stiles interior, and filler members insertable and removable through said openings without disturbing the frame structure.
3. A hollow sheet metal sash having edge openings in longitudinal alinement with the rails and stiles, and filler members insertable and removable through said openings without disturbing the frame structure.
4. A hollow sheet metal sash having openings at the top in line with the stiles and openings at the side in line with the rails, and filler members insertable and removable through said openings.
5. A hollow sheet metal sash having openings at the top in line with the stiles and openings at the side in line with the rails, the rails and stiles being otherwise tubular, and filler members insertable and removable 50 through said openings.
6. A hollow sheet metal sash having openings at the top in line with the stiles and openings at the side in line with the rails, and filler members insertable and removable

through said openings, in combination with 65 removable adjunctive sash elements, and securing means for said elements passing through the rails and stiles into an anchorage within the filler members.

7. A hollow sheet metal sash having openings at the top in line with the stiles and openings at one side in line with the rails, the rails and stiles being otherwise tubular, and wood filler members insertable and removable through said openings, in combination with removable glazing beads, and securing screws for said beads passing through the rails and stiles into an anchorage within the filler members.

8. A hollow sheet metal sash having openings at the top in line with the stiles and openings at one side in line with the rails, the rails and stiles being otherwise tubular, and wood filler members insertable and removable through said openings, in combination with removable glazing beads, weather strips and sash cushions, and securing screws for said elements passing through the rails and stiles into an anchorage within the filler members.

9. In metal sash construction, a hollow frame member including a permanent glass-retaining bead and having an exterior channel in the plane of the sash, a wooden filler member disposed within the channel alongside the bead and serving as an anchorage for a removable glazing bead, said filler member insertable and removable without disturbing the structure of the frame member.

10. A hollow sheet metal sash comprising a frame formed to provide exterior channels at the top and bottom of the sash, filler inserts disposed within the channels and insertable and removable without disturbing the structure, and adjunctive sash elements secured in the filler inserts.

11. A hollow sheet metal sash comprising a frame formed to provide exterior channels at the top and bottom, filler inserts of wood disposed within the channels, and a weather strip and sash cushion secured in the filler inserts respectively.

12. The combination with a sash, and its glass, of fillet aprons separate from the sash frame and overlying the corner area of the glass to protect and facilitate the cleaning of the same.

13. The combination with a sash, and its glass, of fillet aprons of resilient sheet metal overlying the corner area of the glass to protect and facilitate the cleaning of the same.

14. The combination with a sash, and its glass, of fillet aprons inserted between the sash and glass overlying the corner area of the glass to protect and facilitate the cleaning of the same, the outline of said aprons

connecting the vertical and horizontal glass boundaries.

15. The combination with a sash, its glass, and the sash hardware, of fillet aprons beneath the hardware to protect and facilitate the cleaning of the same, the said aprons of curved outline tangent to the vertical and horizontal glass boundaries and extending into the glass field beyond the sash hardware, and means to press the outline of said aprons against the glass surface.

16. A sash frame provided at the inner corner thereof with a transversely yieldable corner member adapted to accommodate it self to varying thicknesses of glass.

17. A sash frame provided at the inner corner thereof with a corner fillet adapted to enter the glass groove in the sash and to exert spring pressure on the glass.

20. 18. The combination with a sash including a fixed glazing bead and a glass seat, of a corner apron of U-cross section adapted to rest on the seat and to receive the glass edge and to overlie the corner area of the 25 same to protect and facilitate the cleaning thereof, the edge of the apron being of curved outline tangent to the vertical and horizontal glass boundaries, and removable glazing beads for holding the corner apron 30 upon the glass and the whole within the sash.

19. In a sash, a yielding glass packing strip of U-cross section having the inner surface of its side walls inclined to the perpendicular.

20. In a sash, a rubber glass packing strip of U-cross section having the inner and outer surfaces of its side walls bounded by outwardly diverging planes.

40 21. In a sash, a yielding glass-packing strip of U-cross section having an exteriorly grooved and interiorly ribbed base.

22. In a sash, a yielding glass-packing strip of U-cross section having an exteriorly 45 grooved and interiorly ribbed base with marginally thickened side walls.

23. In a sash, a glass-packing strip of rubber having a U-cross section with an exteriorly grooved base and marginally 50 thickened side walls.

24. In a sash, a rubber glass-packing strip of U-cross section having an exteriorly grooved and interiorly ribbed base with marginally thickened side walls and outwardly beveled edges.

25. The combination with a sash and its channel guide, of a resilient sash cushion having a heel and a toe portion separated by a longitudinal groove, the cushion including heel and toe having a transverse dimension greater than the channel guide the toe 60 cut away at the end of the cushion to enable

the latter to enter and travel within the channel guide.

26. The combination with a sash, and its 65 channel guide, of a resilient sash cushion having a heel and a toe portion separated by a longitudinal groove, the cushion including heel and toe having a transverse dimension greater than the channel guide the toe arranged to bear on the window sill substantially beneath the outer line of the sash and to overlie the sill in contact therewith in front of the sash.

27. The combination with a sash, of a 75 resilient sash cushion having a heel and a toe portion separated by a longitudinal groove, and an attaching strip disposed longitudinally of the cushion in the groove and having inclined marginal portions acting 80 on the heel and toe portions laterally.

28. The combination with a sash having a channel in its lower edge, of a resilient sash cushion seated within said channel and having a heel and a toe portion separated 85 by a longitudinal groove, and an attaching strip disposed longitudinally of the cushion in the groove and having inclined marginal portions acting on the heel and toe portions laterally.

29. In a sash the combination of a permanent laterally supporting glazing bead, a ledge transverse thereto for supporting the glass edgewise, and a marginal rib, in combination with a removable glazing bead 95 adapted to cooperate with the rib along the inner edge of the sash.

30. In a sash, the combination with a permanent glazing bead, and a glass-supporting ledge of a raised bearing along the inner edge of the sash adapted to cooperate in securely holding the glass in the frame said bearing lying without the plane of said ledge whereby to permit the glass to be transversely introduced into the frame.

31. In a sash the combination of a permanent glazing bead, the inner face of the sash member extending horizontally therefrom, across the plane of the glass to form a glass-supporting ledge and then inclined outwardly away from the horizontal and then inwardly to a point short of the said horizontal, and a removable glazing bead arranged to seat along one edge against the glass and along the other edge against the inner surface of the last mentioned inclined portion of the sash face.

In witness whereof I have hereunto signed my name in the presence of two subscribing witnesses.

GEORGE H. FORSYTH.
